[57] CLAIM

The ornamental design for a firewood support unit, as shown and described.

DESCRIPTION

FIG. 1 is a perspective view of a firewood support unit,
showing my new design;

FIG. 2 is a front elevation view thereof, the rear being a mirror image of that shown;

FIG. 3 is a side elevation view thereof, the opposite side being a mirror image of that shown;

FIG. 4 is a top plan view thereof.

FIG. 5 is a bottom plan view thereof.

FIG. 1

FIG. 2
